US0D1055319S

(12) **United States Design Patent** (10) Patent No.: **US D1,055,319 S**
(45) Date of Patent: ** Dec. 24, 2024

(54) **CEILING PANEL**

(71) Applicant: **Apple Inc.**, Cupertino, CA (US)

(72) Inventors: **Juan Fernandez Royo**, Keaau, HI (US); **Karim Ayache**, London (GB); **Megan Suyehira**, Oakland, CA (US); **Gregory James Ranes**, Redwood City, CA (US); **Karim Alexis Akika**, London (GB); **Paul N. Wass**, Maidstone (GB); **Adeline Piel**, London (GB); **Manish Jain**, New Delhi (IN); **Ashish Jain**, New Delhi (IN); **Stefan Behling**, London (GB); **David Summerfield**, London (GB)

(73) Assignee: **Apple Inc.**, Cupertino, CA (US)

(**) Term: **15 Years**

(21) Appl. No.: **29/863,699**

(22) Filed: **Dec. 21, 2022**

Related U.S. Application Data

(63) Continuation of application No. 29/738,634, filed on Jun. 18, 2020, now Pat. No. Des. 973,918.
